US0D1100880S

(12) **United States Design Patent** (10) Patent No.: **US D1,100,880 S**
(45) Date of Patent: ** Nov. 4, 2025

(54) **HEADPHONE BAND**

(71) Applicant: **Sonos, Inc.**, Goleta, CA (US)

(72) Inventors: **Vincent Shyu**, Goleta, CA (US); **Aki Laine**, Goleta, CA (US); **Dana Krieger**, Goleta, CA (US); **Philippe Vossel**, Wuppertal (DE)

(73) Assignee: **SONOS, INC.**, Goleta, CA (US)

(**) Term: **15 Years**

(21) Appl. No.: **29/993,105**

(22) Filed: **Mar. 12, 2025**

Related U.S. Application Data

(63) Continuation of application No. 29/971,755, filed on Nov. 5, 2024, now Pat. No. Des. 1,070,809, which is a continuation of application No. 29/926,153, filed on Jan. 29, 2024, now Pat. No. Des. 1,055,024, which is a continuation of application No. 29/869,395, filed on Dec. 29, 2022, now Pat. No. Des. 1,019,600, which is a continuation of application No. 29/864,135, filed on May 10, 2022, now Pat. No. Des. 974,327, which is a continuation of application No. 29/737,182, filed on Jun. 5, 2020, now Pat. No. Des. 954,019.

(57) **CLAIM**

The ornamental design for a headphone band as shown and described.

DESCRIPTION

FIG. 1 is a perspective view of a headphone band showing the new design.

FIG. 2 is a second perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The features shown in broken lines do not form part of the claimed design.

The dot-dash broken lines illustrate boundary lines and form no part of the claimed design.

1 Claim, 7 Drawing Sheets
